UNITED STATES PATENT OFFICE.

FRED B. COREY, OF SCHENECTADY, NEW YORK, ASSIGNOR TO GENERAL ELECTRIC COMPANY, A CORPORATION OF NEW YORK.

BLOCK SYSTEM.

No. 850,738.

Specification of Letters Patent.

Patented April 16, 1907.

Application filed October 20, 1905. Serial No. 283,616.

To all whom it may concern:

Be it known that I, FRED B. COREY, a citizen of the United States, residing at Schenectady, in the county of Schenectady and 5 State of New York, have invented certain new and useful Improvements in Block Systems, of which the following is a specification.

My invention relates to block systems for 10 railways, and especially to a system which is used on many single-track roads in England and elsewhere and which is known as the "staff" system. In that system the conductor of a train, upon arriving at a block, 15 receives from an attendant in charge of the block a staff, indicating that the block is clear. The train accordingly proceeds through the block, and upon reaching the other end the conductor hands the staff to 20 the attendant stationed at that end of the block. The block is thus cleared, and the staff may be handed by the attendant to the conductor of a train bound in the opposite direction. This system has the advantage of 25 great safety, since the chance of two trains bound in opposite directions being admitted into the same block is reduced to a minimum. The system is open to the objection that it requires an attendant for every block and, 30 furthermore, that when the number of trains in one direction is at any time in excess of the number of those bound in the opposite direction, as is frequently the case on suburban roads in certain hours of the day, the 35 simplicity of the system is lost, and in order to maintain its safety considerable complication in the matter of the delivery of staves is required.

The object of my invention is to provide an 40 automatic system which shall not only do away with the attendants for the blocks, but shall also permit any desired number of trains bound in the same direction to enter the block, while giving each train warning 45 that there is a train ahead of it and while absolutely preventing the entrance into the block of any train bound in the opposite direction.

My invention will best be understood by 50 reference to the accompanying drawings, in which—

Figure 1 shows diagrammatically an automatic staff system arranged in accordance with my invention. Fig. 2 shows an eleva-

tion in cross-section of a staff-box and controlling-magnets therefor adapted to my invention, and Fig. 3 shows a plan view in cross-section of the same.

Referring first to Fig. 1, A and A' represent two stations at opposite ends of the 60 block of a single-track railway. The mechanism at each station comprises a disk B, having ratchet-teeth on each side, which teeth are engaged by the two pawls C, by means of which the disk may be rotated in 65 either direction. The disk B carries two contact-rings D, upon which bear the brushes d. The contact-rings D are connected to alternate-contacts e, carried by disk B. Disk B also carries the contact F, which when disk B 70 is rotated in a counter-clockwise direction bridges the stationary contacts f.

Each of the pawls C is operated by a magnet-winding or solenoid G, which when energized draws the pawl down against the pull 75 of the tension-spring g and rotates disk B one notch. Pawls C are also arranged to be acted upon by the solenoids H, which when energized withdraw the pawls from engagement with the ratchet-teeth.

h is a contact in engagement with contacts e.

I represents a battery or other source of current for the system.

L and S represent two coils, which I designate as "locking" and "safety" coils, respectively, and which control the withdrawal of staves from the staff-box, which is not shown in this figure and which will be explained later. For the present it is sufficient to understand that as long as either locking- 85 coil L or safety-coil S remains energized no staff can be drawn from the box, but that to permit withdrawal it is necessary that both coils be deenergized and then one or both again energized.

J represents a pair of contacts which are arranged to be bridged by a contact carried by the staff when the staff is withdrawn, as will be explained later.

R is a resistance in series with locking- 90 coil L.

Neglecting for a moment the details of operation of the staff-box and its magnets, the operation of the system is as follows: Assume that the block is clear and that a train 105 arrives at station A. With the block clear the two disks B and B' at the two stations will be in the positions shown in the figures,

and all the circuits will be as shown. It will be seen that the circuits of locking-magnets L and L' are open at the contacts F and F', but that the circuits of the safety-magnets 5 are closed as follows: from battery I, through safety-magnet S, to contact h, to one of the contacts e, to the outer ring D, to brush d, to line 2, to brush d', to outer ring D', to one set of contacts e', to contact h', 10 through magnet-coil S'; to battery I', to ground, and back to battery I. As has been already said, no staff can be withdrawn while either the locking or the safety magnets remain energized. As has been seen, the 15 safety-magnets S and S' are energized, and consequently with the circuits in this condition no staves can be withdrawn. If, however, the conductor of a train at station A endeavors to withdraw a staff, the contact carried thereby will bridge contacts J, as will be hereafter explained, and a circuit will be 20 closed as follows: from battery I, through contacts J, through right-hand solenoid G, through left-hand solenoid H, to line 1, through right-hand solenoid H', through left-hand solenoid G', to battery I', to ground. Right-hand pawl C and left-hand pawl C' will consequently be drawn down by their 25 solenoids, rotating disk B one notch in a clockwise direction and disk B' one notch in a counter-clockwise direction. Meanwhile left-hand pawl C and right-hand pawl C' will have been retracted by their solenoids H and H', allowing the disks to turn freely. At the 30 same time the circuit of the safety-magnets S and S' is momentarily broken at the points of contact between contact h and a contact e and between contact h' and a contact e'. Both the locking and the safety magnets at 35 station A are consequently deenergized, which is the first step necessary for the withdrawal of a staff. Moreover, by the rotation of both disks one notch the circuit of safety-magnets S and S' has again been closed, but 40 this time through the inner rings D D', line-wire 3, and the other set of contacts e e'. This, as has been already stated, is the second step necessary for the withdrawal of a staff, and consequently the staff at station A 45 may now be withdrawn. By the rotation of disk B', however, contact F' has been brought into engagement with contacts f' and the circuit of locking-magnet L' has been closed. No staves can be withdrawn, therefore, at station A', and the block is closed to all trains 55 coming from that direction.

After the staff has been withdrawn at station A, thereby opening the circuit at contacts J, all of the pawls are released by their 60 solenoids and are returned to the positions shown in the drawings, leaving the disks, however, rotated one notch, as has been described. Accordingly, if a second train reaches station A bound in the same direction as the first the conductor of that train

can withdraw another staff from the box and proceed into the block. The displacement of disk B, however, from its normal position will indicate to him that there is a train ahead of him in the block, and consequently 70 he can proceed with the train under control. The withdrawal of a second staff at station A rotates both disks another notch, but still leaves it possible for another train following in the same direction to enter the block. 75 The staff-box at station A, however, still remains closed against all trains bound in the opposite direction, since contact F' still remains in engagement with disk f', thus maintaining the circuit of locking-magnet L' 80 closed. Now assume that the first train has reached the end of the block. Although the staff-box at station A' is locked, so as to prevent the withdrawal of a staff, it is so arranged that a staff may be inserted, as will be 85 explained hereafter. As the conductor of the first train inserts the staff in the box at A' the contact carried thereby will bridge the contacts J', thereby completing a circuit, as follows: from battery I', through contacts 90 J', through right-hand solenoid G', through left-hand solenoid H' to line 4, through right-hand solenoid H, through left-hand solenoid G, to battery I, to ground. Each ratchet-wheel will consequently be rotated 95 one notch in the opposite direction to that in which it was displaced by the withdrawal of a staff at station A—that is, each wheel will be returned one notch toward its original position. This will be repeated as each successive train in the block arrives at station A' and its conductor returns his staff to the box at A'. When the same number of staves have been returned to station A' that were 100 withdrawn from station A, the disks will have 105 been returned to their original position and the block will again be clear. It will be seen that with this arrangement any desired number of trains bound in the same direction may be admitted to any block with warning to 110 each train that another is ahead of it, and at the same time the block will be maintained closed against all trains bound in the opposite direction.

A staff-box adapted to the system that has 115 been described is shown in Figs. 2 and 3. M represents the casing of the staff-box, and K represents the staves therein. The staves are shaped as shown and are made of any insulating material, such as wood, and carry the contact-strip k, arranged to bridge the contacts J, supported from the box-easing, when the staff is withdrawn. The staff K is arranged with two holes u and v, which are adapted to be engaged by the dog T and by 120 the rod P, respectively. Rod P is carried at one end of the bar O, pivoted at o, which carries at its other end a yoke-supporting rod N. Rod N carries at its upper end the dog T and at its lower end movable core s. 125 l is a 130

stationary core surrounding rod N. L and S are the locking and safety magnets, respectively. It will be seen that if either coil L or S is energized and it is attempted to withdraw a staff, dog T, which engages the hole u, will be drawn forward to the position shown in dotted lines and will prevent further withdrawal of the staff. At this point, however, contact-strip k bridges contacts J. In the operation of the system, as has already been explained, this bridging of contacts J results in opening the circuit of coil S, core s falls, rotating bar O on its pivot, lowering dog T out of engagement with the hole u, and raising rod P into engagement with the hole v. Although the staff is thus released by dog T, it is nevertheless still locked by the rod P. When, however, the circuit of coil S is again closed by the rotation one notch of the disks, as has been already described, core s is again drawn up, rod P is depressed, releasing staff K, and dog T, although it is again raised, does not enter the hole u, since the spiral spring t throws dog T over to the position shown in full lines and causes it to engage the under side of staff K back of the hole u. Staff K may thus be withdrawn. This operation is repeated every time that a staff is withdrawn at the station. It will be seen that if locking-magnet L is energized core S will be drawn up, and as long as it is held in its raised position no staff can be withdrawn from the box. Furthermore, it will be seen that owing to the shape of dog T a staff can be inserted into the box at any time while either coil L or S is energized by simply raising the outer end of the bottom staff in the box and sliding the staff which is to be inserted underneath it. This brings the staff last inserted at the bottom of the pile, so that it will be the first to be withdrawn.

Referring again to Fig. 1, it will be seen that two sets of contacts e are provided for each wheel or disk. These sets are formed by connecting alternate contacts together and insulating each set from the other. The purpose of this is to provide an automatic check upon the operation of the machines and to close the block against all trains in case one or both of the machines becomes disabled, so as to prevent its proper operation. If when an attempt is made to withdraw the first staff neither machine rotates, the circuit of the safety-magnet is not broken, and the staff cannot be withdrawn. If, on the other hand, one disk rotates while the other remains stationary, the circuit of the safety-coil S is not again closed, and in this case also no staff can be withdrawn. Thus all chance of trains entering the block in opposite directions because of injury to the staff mechanism is eliminated.

While I have shown a complete block system and described all the parts in detail, it will be obvious that many changes may be

made in the construction of the parts and in the arrangement of circuits without departing from the spirit of my invention. For instance, the form of the staff may be radically changed and the means whereby the locking mechanism is operated by the withdrawal of a staff may be varied in any way without departing from my invention. Accordingly, I desire it to be understood that when the word "staff" is used in the appended claims I do not intend to limit its meaning to the particular form of staff shown in the drawings, but to designate thereby any article of any form or shape whatsoever which is adapted to serve as a token in my system and by its withdrawal to actuate a locking mechanism. Accordingly, it will be understood that I do not desire to limit myself to the particular construction and arrangement of parts here shown, since changes therein which do not depart from the spirit of my invention will be obvious to those skilled in the art.

What I claim as new, and desire to secure by Letters Patent of the United States, is—

1. In a block system, two staff-boxes, a plurality of staves in each box, said boxes being arranged normally to permit the withdrawal of one staff at a time from either box, and means operative upon the withdrawal of a staff from one box to lock the second box against withdrawal of staves.

2. In a block system, two staff-boxes, a plurality of staves in each box, said boxes being arranged normally to permit the withdrawal of one staff at a time from either box, means operative upon the withdrawal of a staff from one box to lock the second box against withdrawal of staves, and means for unlocking said second box operative upon the insertion of said staff therein.

3. In a block system, two staff-boxes, a plurality of staves in each box, said boxes being arranged normally to permit the withdrawal of one staff at a time from either box, a step-by-step mechanism operative upon the withdrawal of each staff from one box and arranged when displaced to lock the second box against withdrawal of staves, and means for moving said mechanism one step in the reverse direction upon the insertion of each staff in the second box.

4. In a block system, two receptacles, staves in each receptacle, a mechanism for each receptacle arranged when displaced in a given direction to lock said receptacle against withdrawal of staves, means operative upon the withdrawal of a staff from either receptacle for displacing both mechanisms but in opposite directions, and means operative upon the insertion of said staff in the other receptacle for returning both mechanisms to their original positions.

5. In a block system, two receptacles, staves in each receptacle, a step-by-step

mechanism arranged when displaced one or more steps in a given direction to lock said receptacle against withdrawal of staves, means operative upon the withdrawal of each 5 staff from one of said receptacles for displacing both mechanisms one step but in opposite directions, and means operative upon the insertion of each of said staves in the other receptacle for returning both mechanisms 10 one step toward their original positions.

6. In a block system, two receptacles, staves in each receptacle, two synchronously but relative oppositely moving mechanisms each arranged when displaced in a given direction to lock one of said receptacles against the withdrawal of staves, means for moving said mechanisms upon the withdrawal of each staff from one receptacle, and means for returning said mechanism by an equal 15 amount toward their original positions upon the insertion of each staff in the second receptacle.

7. In a block system, two receptacles, staves in each receptacle, two ratchet-wheels 25 each arranged when moved in a given direction to lock one of said receptacles, pawls adapted to move said ratchet-wheels in either direction, means operating said pawls to move said ratchet-wheels in relatively opposite directions, upon the withdrawal of a staff from either receptacle, and means for operating said pawls to move said ratchet-wheels in the reverse directions upon the insertion of a staff in the other receptacle.

35 8. In a block system, two receptacles, staves in each receptacle, two ratchet-wheels each arranged when moved in a given direction to lock one of said receptacles, pawls adapted to move said ratchet in either direction, means for operating said pawls to move said ratchet-wheels one step in relatively opposite directions upon the withdrawal of each staff from one of said receptacles, and means for operating said pawls 40 to return said wheels one step in the reverse direction upon the insertion of each of said staves in the second receptacle.

9. In a block system, two receptacles, staves therein, a mechanism for each receptacle controlling the withdrawal of staves therefrom and arranged normally to permit the withdrawal of one staff at a time, means operative upon the withdrawal of one or more staves from one of said receptacles for locking the mechanism controlling the second receptacle to prevent withdrawal of staves therefrom, and means for unlocking said mechanism only upon the insertion in the second receptacle of staves equal in number to those withdrawn from the first receptacle.

10. In a block system, two receptacles, staves in each receptacle, an electrically-controlled locking mechanism for each receptacle, a circuit arranged to be closed upon

the withdrawal of a staff from either receptacle and when closed to energize the locking mechanism of the other receptacle, and a circuit arranged to be closed by the insertion of a staff in the other receptacle and when closed to energize the locking mechanism of that other receptacle to unlock said receptacle.

11. In a block system, two receptacles, staves in each receptacle, an electrically-controlled locking mechanism for each receptacle arranged normally to permit the withdrawal of one staff at a time, and circuits for said mechanisms energized upon the withdrawal and insertion of staves in said receptacles whereby one of said mechanisms is energized to lock its receptacle upon the withdrawal of one or more staves from the other receptacle and to unlock its receptacle upon the subsequent insertion in its receptacle of an equal number of staves. 75

12. In a block system, two receptacles, staves in each receptacle, a mechanism for each receptacle arranged when displaced in a given direction to lock said receptacle against withdrawal of staves, means operative upon the withdrawal of a staff from either receptacle for displacing both mechanisms but in opposite directions, and means operative upon the failure of either mechanism to move 90 for preventing the complete withdrawal of said staff.

13. In a block system, two receptacles, staves in each receptacle, a locking mechanism operative upon the withdrawal of a staff from one receptacle to lock the other receptacle, and means operative upon the failure of said mechanism to operate for preventing the complete withdrawal of said staff. 100

14. In a block system, two receptacles, staves in each receptacle, a locking mechanism for each receptacle, two coils controlling each locking mechanism, and means operative upon the partial withdrawal of the staff from one receptacle to vary the circuits of said coils to permit the complete withdrawal of said staff and to lock the other receptacle 110 against withdrawal of staves.

15. In a block system, two receptacles, staves in each receptacle, a locking mechanism for each receptacle, two coils controlling each locking mechanism, one coil being normally open-circuited and the other normally closed-circuited and said coils being arranged to permit the complete withdrawal of a staff upon the opening of the circuit of both coils, and then closing the circuit of one coil, and means operative upon the partial withdrawal of a staff from one receptacle to open and then close again the circuit of the normally closed-circuited coil of that receptacle and to close the circuit of the normally open-circuited coil of the other receptacle. 115 120 125

16. In a block system, two staff-boxes, a locking mechanism for each box, two coils 130

controlling each locking mechanism; a step-by-step mechanism operative upon the partial withdrawal of a staff from one box and arranged to vary the circuits of said coils to permit the complete withdrawal of the staff from that box and to lock the other box against withdrawal of staves, and means for moving said mechanism one step in the re-

verse direction upon the insertion of a staff in the second box.

In witness whereof I have hereunto set my hand this 13th day of October, 1905.

FRED B. COREY.
